UNITED STATES PATENT OFFICE

LOUIS H. MENDELSON, OF PATERSON, NEW JERSEY

DESIGN FOR A STOCKING.

Application filed April 12, 1928. Serial No. 26,295. Term of patent 14 years.

To all whom it may concern:

Be it known that I, LOUIS H. MENDELSON, a citizen of the United States, residing at Paterson, in the county of Passaic and State of New Jersey, have invented a new, original, and ornamental Design for a Stocking, of which the following is a specification, reference being had to the accompanying drawing, forming part thereof.

I claim:

The ornamental design for a stocking, as shown.

LOUIS H. MENDELSON.
